CLAIM

The ornamental design for a protective case, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top, right, front perspective view of a protective case showing a first embodiment of the new design;

FIG. 2 is a right, rear, top perspective view of the invention illustrated in FIG. 1;

FIG. 3 is a front view of the invention illustrated in FIG. 1;

FIG. 4 is a rear view of the invention illustrated in FIG. 1;

FIG. 5 is a right side view of the invention illustrated in FIG. 1;

FIG. 6 is a left side view of the invention illustrated in FIG. 1;

FIG. 7 is a top view of the invention illustrated in FIG. 1;

FIG. 8 is a bottom view of the invention illustrated in FIG. 1;

FIG. 9 is a top, right, front perspective view of a protective case showing a second embodiment of the new design;

FIG. 10 is a right, rear, top perspective view of the invention illustrated in FIG. 9;

FIG. 11 is a front view of the invention illustrated in FIG. 9;

FIG. 12 is a rear view of the invention illustrated in FIG. 9;

FIG. 13 is a right side view of the invention illustrated in FIG. 9;

FIG. 14 is a left side view of the invention illustrated in FIG. 9;

FIG. 15 is a top view of the invention illustrated in FIG. 9;

(Continued)

FIG. 16 is a bottom view of the invention illustrated in FIG. 9;
 FIG. 17 is a top, right, front perspective view of a protective case showing a third embodiment of the new design;
 FIG. 18 is a right, rear, top perspective view of the invention illustrated in FIG. 17;
 FIG. 19 is a front view of the invention illustrated in FIG. 17;
 FIG. 20 is a rear view of the invention illustrated in FIG. 17;
 FIG. 21 is a right side view of the invention illustrated in FIG. 17;
 FIG. 22 is a left side view of the invention illustrated in FIG. 17;
 FIG. 23 is a top view of the invention illustrated in FIG. 17;
 FIG. 24 is a bottom view of the invention illustrated in FIG. 17;
 FIG. 25 is a top, right, front perspective view of a protective case showing a fourth embodiment of the new design;
 FIG. 26 is a right, rear, top perspective view of the invention illustrated in FIG. 25;
 FIG. 27 is a front view of the invention illustrated in FIG. 25;
 FIG. 28 is a rear view of the invention illustrated in FIG. 25;
 FIG. 29 is a right side view of the invention illustrated in FIG. 25;
 FIG. 30 is a left side view of the invention illustrated in FIG. 25;
 FIG. 31 is a top view of the invention illustrated in FIG. 25; and,
 FIG. 32 is a bottom view of the invention illustrated in FIG. 25.

The broken lines in the drawings depict portions protective case that form no part of the claimed design. The parallel diagonal shading lines on the protective case in the embodiment of FIGS. 1-8 indicate translucency.
